JESSE A. MASON, OF MANNINGTON, WEST VIRGINIA.

CASING-COUPING.

1,141,910.

Specification of Letters Patent.

Patented June 1, 1915.

Application filed April 10, 1914. Serial No. 831,059.

To all whom it may concern:

Be it known that I, JESSE A. MASON, a citizen of the United States of America, and resident of Mannington, county of Marion, 5 and State of West Virginia, have invented certain new and useful Improvements in Casing-Couplings, of which the following is a specification.

This invention relates to couplings de- 10 signed for use in connection with well cas- ing or tubing, and it has for its primary object to provide a coupling for deep-well cas- 15 ing which will permit of the ready re- moval or withdrawal of such casing from the well.

Hitherto the couplings universally used have been formed with a well-defined, or pronounced, external annular inwardly-directed bevel or rounded shoulder at each 20 of its ends. Due to this beveled or rounded shoulder, much trouble is experienced in withdrawing the casing, and many millions of feet of the latter are yearly left in aban- 25 doned oil and gas wells because of inability to withdraw it. The cause of the difficulty will be realized when it is understood that earth caves in and settles close around the casing at occasional points throughout the 30 depth of the well, and that, to withdraw the string of casing, the couplings, which have a diameter greater than that of the casing, must be drawn through the casing-embracing 35 earth, displacing the latter. In elevat- 40 ing the string of casing the beveled or rounded upper end of the couplings acts to exert upon the embracing earth a wedging pressure which forces said earth outward and upward, the line of force exerted by such coupling upon said earth being at sub- 45 stantially an angle of 45 degrees to the axis of the well. As the string is elevated, the resistance offered by the embracing earth constantly increases, due to the fact that said earth is constantly becoming more com- 50 pact with the elevation of the coupling thereagainst. With such resistance, added to the great suspended weight of a long string of casing, it frequently happens that, after an elevation of a few feet, it is utterly 55 impossible to apply sufficient power to accom- plish a further elevation. In like manner the lower end of the coupling acts to prevent the casing from being lowered. Thus, the casing becomes stuck fast in the 60 hole and must be abandoned, oftentimes result- 65 ing in a great financial loss. Furthermore,

the use of the common form of coupling frequently results in the spreading and conse- 60 quent breakage of the elevators employed in elevating the casing. This is due to the fact that the lower beveled or rounded end 65 of the coupling engaged by the clamp mem- bers of the tool exerts, under the stress im- posed by the great weight of the suspended casing, even under the most favorable ele- 70 vating conditions, a wedging force upon said members which tends to spread the latter in a manner well understood by those skilled in the art.

It is the object of the present invention, 70 therefore, to obviate the difficulties above noted, and this is attained by the provision of a coupling of an extremely simple and inexpensive form, the nature of which will hereinafter be fully explained, reference be- 75 ing had to the accompanying drawings, forming a part of this specification, in which—

Figure 1 is a sectional view of a well, 80 showing in side elevation, a string of casing disposed therein, the casing sections being connected by means of my improved coupling, and showing the earth from the walls of the well closing the space around the cas- 85 ing; and Fig. 2 is an enlarged sectional view 85 of the coupling applied to two adjacent cas- ing sections.

Referring to said drawings, in which like designating characters distinguish like parts throughout the several views—1 indicates 90 the sections of a oil or gas well casing which have their ends threaded exteriorly, as ordinarily, and 2 indicates the interiorly threaded sleeve-like body of my improved coupling, the same being of uniform exterior 95 diameter from end to end and presenting clean-cut circumferential end-surfaces 3 which are disposed at right angles to the axis of the body 2.

Casing the sections of which are connected 100 by means of my couplings may be readily withdrawn from the well, the squared ends of the couplings readily cutting their way upward through, and thus clearing the cou- 105 pling, of obstructions instead of forcing the latter outward. There is no tendency, there- 110 fore, to force or wedge the earth in an upward and outward direction until the latter becomes so compact as to resist further elevation, as is the case when the above-men- 115 tioned common form of coupling is em- ployed. In practice, a cutting edge is pre-

sented at the circumferential angle 4 which, when the casing is being elevated, cuts directly through, and does not tend to wedgely compact, earth which lies in embracing relation to the casing. Furthermore, the plain shoulder presented by the lower end of the coupling affords a positive seat for the clamp members 5 of the elevator employed for elevating the casing. Thus the 5 tendency to wedgely spread said clamp members apart, encountered in the use of the common form of coupling, as hereinbefore explained, is wholly obviated. This is an important feature, since, in addition to 10 the breakage of elevators resulting from the spreading of the clamp members when the common form of coupling is used, it frequently happens, in lowering casing into a well, that, due to the great weight of suspended casing, the clamp members are 15 spread apart by the coupling to an extent that the lower body portion of the coupling wedges down between said members where it partially collapses under the excessive gripping force. When the coupling is thus distorted or collapsed it is difficult, if not 20 wholly impossible, to introduce the next joint, or casing section, within the coupling. 25

While the change from the common form of coupling to the improved form constituting the present invention might appear slight to those not skilled in the art, such change results in the production of a device which permits of the recovery of casing which, with the preexisting form, has been wholly irrecoverable and which, in the oil and gas fields of the United States, totals annually many millions of feet. 30 35

What is claimed is—

The combination with the adjacent exteriorly threaded ends of well-casing sections, of a coupling therefor comprising an interiorly threaded sleeve-like body the exterior diameter of which is uniform throughout and greater than that of said sections, each 40 end of said body presenting a plane circumferential surface disposed at right angles to the axis and constituting a projecting earth cutting shoulder. 45

In testimony whereof, I affix my signature 50 in presence of two subscribing witnesses.

JESSE A. MASON.
